UNITED STATES PATENT OFFICE.

WILLIAM HOOPER, OF TICONDEROGA, NEW YORK, ASSIGNOR TO HIMSELF
AND JOHN R. DE LAMAR, OF DENVER, COLORADO.

ORE-CONCENTRATOR.

SPECIFICATION forming part of Letters Patent No. 337,683, dated March 9, 1886.

Application filed August 31, 1885. Serial No. 175,812. (No model.)

To all whom it may concern:

Be it known that I, WILLIAM HOOPER, of Ticonderoga, in the county of Essex and State of New York, have invented certain new and 5 useful Improvements in Ore Concentrators, of which the following is a full, clear, and exact description.

Reference is to be had to the accompanying drawings, forming a part of this specification, 10 in which similar letters of reference indicate corresponding parts in all the figures.

Figure 1 is a sectional side elevation of one 15 of my improved ore-concentrators. Fig. 2 is a sectional plan view of the same, parts being omitted and parts being broken away. Fig. 3 is a plan of the annular bar, the radial arms R, and the bars Q, the sleeve parts being broken away and the shaft A in section; and Fig. 4 is a central vertical section, the shaft 20 A being omitted.

The object of this invention is to provide ore-concentrators constructed in such a manner as to separate automatically the floating values, tailings, middlings, and concentrates, 25 and which shall be reliable in operation, preserving all the metal.

The invention consists in the construction and combination of various parts of the ore-concentrator, as will be hereinafter fully de- 30 scribed, and then pointed out in the claims.

A represents a vertical shaft, the upper part of which revolves in bearings in the frame B of the machine, or of the building in which the said machine is placed. The lower end of the 35 shaft A revolves in a step, C, secured to the floor of the building, the frame of the machine, or other suitable support.

Upon the lower part of the shaft A is placed a loose sleeve, D, to the lower end of which is 40 attached a large beveled gear-wheel, E. The teeth of the beveled gear-wheel E mesh into the teeth of the beveled pinion-wheel F, attached to the inner end of the shaft G, which revolves in supports H, attached to the floor of 45 the building, or to the frame of the machine. To the outer end of the shaft G is attached a fast pulley, I, and a loose pulley, J, to receive a driving-belt from any convenient power.

To an arm formed upon the upper end of 50 the sleeve D is attached a radial beam, K,

To the beam K are attached bearings, in which revolves a shaft L. To the inner end of the shaft L is attached a beveled pinion-wheel, M, the teeth of which mesh into the teeth of the beveled gear-wheel N, attached to the shaft A. 55 To the outer end of the shaft L is attached a crank-wheel, O, to the crank-pin of which is pivoted the end of the connecting-rod P. The crank-wheel O is slotted radially to receive its crank-pin, so that the said crank-pin can be 60 readily adjusted to give a longer or shorter throw to the crank, as may be required. The other end of the connecting-rod P is pivoted to a support attached to or formed upon a radial bar, Q, the inner end of which is attached 65 to an arm, R, formed upon the lower end of the sleeve S, placed upon the shaft A. Eight (more or less) radial bars, Q, may be used, which are placed at equal distances from each other, are attached at their inner ends to arms 70 R of the sleeve S, and attached at their outer ends to an annular bar, T.

To the annular bar T are hinged, at a little distance from their outer ends, the radial bars U. The inner ends of the radial bars U are 75 hinged to a sleeve, V, sliding up and down upon the upper part of the sleeve S, and carried around by and with the said sleeve S in its revolution.

Upon the upper part of the sleeve V is swiv- 80 eled a ring, W, to the opposite sides of which are pivoted the lower ends of the rods X. The rods X pass up at the opposite sides of the shaft A, and are pivoted at their upper ends to the forked end of the lever Y, which is fulcrumed 85 to the lower end of the hanger Z. The upper end of the hanger Z is attached to the frame B. The outer end of the lever Y is perforated to receive the pin a, which passes through it and through one of a series of perforations in 90 a bar, b, pivoted at its upper end to the frame B, so that the lever Y can be secured in any position into which it may be adjusted. With this construction, by operating the lever Y the sleeve V and the inner ends of the bars U, and 95 with them the inner ends of the sluices e, can be raised and lowered to give any desired inclination to the said sluices. The sluices e are secured to the hinged radial bars U, are placed side by side, and are widened toward 100

their outer ends, so as to form an annular series of sluices.

d is the stirring-tub, which is supported by bars *e*, attached to the frame of the machine, or 5 to some other suitable support. The pulverized ore and water are introduced into the stirring-tub *d* through a spout, *f*, and are kept mixed by an agitator, *g*, attached to the lower end of a vertical shaft, *h*, the upper part of 10 which is journaled in the frame *B*. To the upper end of the shaft *h* is attached a pulley, *i*, to receive a driving-belt, which also passes around a pulley, *j*, attached to the upper end of the vertical shaft *A*, so that the said agitator will be driven from the said vertical shaft. The vertical shaft *A* is also provided with a pulley, *k*, to receive a driving-belt from any convenient power. The ore and water from the stirring-tub *d* escape through faucets *l* into 15 the spouts *m*, by which they are conducted into the head ends of the sluices *c*. The spouts *m* are supported from the frame *B* by rods *n*, as shown in Fig. 1. Beneath the lower ends of the sluices *c* is placed a circular trough, *o*, 20 which is divided into sections *p q r s* by cross-partitions *t*, to grade the material as it is discharged from the sluices *c*, each section having an opening, *u*, through which the material received in it can be drawn off, or allowed to 25 flow into suitable receivers. The trough *o* is stationary, and is secured to posts *v*, or other suitable supports. As the sluices *c* receive ore and water from the stirring-tub *d* and pass away from the feed-spouts *m*, more water is introduced into them from a perforated 30 pipe, *w*, connected with a supply-pipe, *x*, and suspended from the frame *B* by rods *y*. With this construction the revolution of the shaft *G* will carry the sleeve *D* and beam 35 *K* around the vertical shaft *A*, and the said beam *K*, by means of the shaft *L* and connecting-bar *P*, will draw bars *Q U*, sleeves *S V*, and sluices *c* with it around the said vertical shaft *A*, so that the said sluices will successively receive ore and water, and at the same 40 time the revolution of the vertical shaft *A*, by means of the gear-wheels *M N*, will rotate the shaft *L*, and thus cause the crank-wheel *O* and connecting-rod *P* to vibrate the bars *Q U*, sleeves *S V*, and sluices *c*, and thus facilitate 45 the passage of the material down the said sluices. As the ore and water enter the sluices *c* the lightest particles of metal, which are known as "floating values," flow off with the water and are received in the section *p* of the trough *o*, the pulverized rock, which is known as "tailings," and is the next lightest part of the material, is received in the section *q* of the trough *o*. The lighter particles of metal and

the heavier particles of rock, and known as 60 "middlings," are received in the third section, *r*, of the trough *o*, and the concentrates, being the heaviest part of the material, are received in the fourth section, *s*. The contents of the several sections are subsequently 65 treated in the usual manner.

Having thus described my invention, I claim as new and desire to secure by Letters Patent—

1. In an ore-concentrator, the combination, with a frame, of an annular series of radial 70 sluices adapted to revolve in a horizontal plane and movably connected to said frame, and mechanism for imparting a vibratory movement to said sluices independent of their rotary movement, substantially as set forth. 75

2. In an ore-concentrator, the combination, with a frame adapted for revolution in a horizontal plane, of a series of annularly-arranged 80 radial sluices, mechanism for raising and lowering the inner ends of said sluices, and mechanism for rotary reciprocating the frame carrying the sluices, as shown and described. 85

3. In an ore-concentrator, the combination, with a vertical shaft, a driving mechanism, a stirring-tub, and a perforated water-pipe, of an 85 annular series of radial flaring sluices adapted to have a rotary movement, substantially as herein shown and described, whereby the head ends of the said sluices will be brought successively beneath the feed and the water supply, as set forth. 90

4. In an ore-concentrator, the combination, with the vertical shaft *A*, its driving mechanism, the rotating sleeve *D*, its driving mechanism, the sleeve *S*, radial arms and bars *R Q*, 95 and annular bars *T*, carrying the annular series of sluices *c*, of the beam *K*, attached to the said sleeve, the shaft *L*, journaled to the said beam, the gear-wheels *M N*, connecting the said shafts, and the crank-wheel and connecting-rod *O P*, substantially as herein shown and described, whereby the said series of sluices will be rotated and at the same time shaken, as set forth. 100

5. In an ore-concentrator, the combination, 105 with the vertical shaft *A*, the sleeve *S*, the radial arms and bars *R Q*, connected with the said sleeve, the annular bar *T*, connecting the said radial bars, and the annular series of sluices *c*, of the sleeve *V*, the hinged radial 110 bars *U*, the ring *W*, connecting-rods *X*, and lever *Y*, substantially as herein shown and described, whereby the inclination of the said sluices can be readily regulated, as set forth.

WILLIAM HOOPER.
